UNITED STATES PATENT OFFICE.

JOSEPH S. RANDALL, OF GRAND RAPIDS, MICHIGAN, ASSIGNOR OF TWO-THIRDS TO WILLIAM S. BARNETT AND WILLIAM H. SIGEL, BOTH OF SAME PLACE.

KEY-FASTENER.

SPECIFICATION forming part of Letters Patent No. 364,296, dated June 7, 1887.

Application filed December 18, 1886. Serial No. 229,014. (No model.)

To all whom it may concern:

Be it known that I, JOSEPH S. RANDALL, a citizen of the United States, residing at Grand Rapids, in the county of Kent and State of Michigan, have invented a new and useful Improvement in Key-Fasteners, of which the following is a specification.

My invention relates to improvements in key-fasteners in which a sliding plate engages with the shank of the key in such a manner as to prevent turning or removing the said key, and also to close the key-hole.

Heretofore, to prevent such plates from being moved by a suitable instrument inserted through the key-hole, such plates have been adapted to spring away from the surface upon which they are placed, and by so doing engage a stop or fastening. This is objectionable, because at all other times the plate is free to move, and after using for a time the pivot upon which the plate turns becomes loosened and the plate may be moved without necessarily springing it enough to engage the stop; also, if the flat side of the key-shank chanced to be presented to the slit in said plate, the shank would not enter the slit until the key was turned into proper position.

The objects of my invention are to provide reliable means for securing said plate in position so that it cannot be moved by a person upon the outside of the door; also, to provide a sliding plate that will automatically turn the key into proper position for securing the same, as will more fully appear in what follows.

In the accompanying drawings, Figure 1 is a perspective view of an escutcheon with my device applied; Fig. 2, a section of the same on the line *x x*, Fig. 1; Fig. 3, an elevation of the side next the door; Fig. 4, an elevation of the sliding plate and a section of the key; Fig. 5, an elevation showing the position of the locking-pin for securing the sliding plate; Fig. 6, an elevation of a rim-lock with my device applied to the same; Fig. 7, a section of the same on the line *y y*, Fig. 6.

Like letters refer to like parts in all the figures.

A is the outer plate of the escutcheon, which is recessed at the back to accommodate the

plate *a*, and has a slot, *d*, through which passes a pin, *C*, for moving and locking said plate *a*. Said slot has at one or both ends a lateral enlargement at its upper side, as shown at *e*, Fig. 5, with which the shank *C* of said pin engages to lock the plate *a*. Said pin has also a flattened outer end convenient for grasping with the thumb and fingers, and passes through a hole in the plate *a*, in which it turns freely, and has rigidly attached to its inner end a cam, *c*, which slides in a chamber in the back plate, *D*, the metal of which is folded, as shown at *b*, to afford a suitable bearing-surface for said cam.

The sliding plate *a* has a key-hole, *f*, which, when said plate is slid to the left as far as it will go, will correspond with the key-hole in the escutcheon-plates *A* and *D*, and extending laterally from said key-hole is a slit, *g*, the upper side of which is in line with the top of the said key-hole and the under side of which is in line with the lower side of the shank of the key when the flat side of said shank is in a horizontal position. The angle formed by the junction of this lower side and the key-hole is rounded, as shown at *h*, to more readily turn the key when coming in contact with the same. The projection *i* on the cam *c* serves as a stop to prevent turning the locking-pin too far. When the device is applied to a rim-lock, as shown in Figs. 6 and 7, the inner plate, *D*, is omitted, the cam *c* acting against the casing of the lock.

The operation of my invention is as follows: The key being in the lock, it has a tendency to turn in the position shown in Fig. 4. As the plate *a* is moved to the right the rounded corner *h* strikes the lower corner of the key-shank and turns the key so that said shank passes into the slot *g* as the plate progresses. When the pin *C* reaches the end of the slot *d*, a partial rotation of said pin causes the cam *c* to raise the shank of said pin into the lateral enlargement *e*, and, acting as a wedge, binds it there, at the same time slightly lifting the plate *a*, which binds the key-shank in the upper part of the key-hole by pressing the plate *a* against its under side.

I am aware that a sliding plate having a slit

or notch adapted to engage with the shank of the key is not new; so, also, that such plate provided with a device that will temporarily secure the said plate when pushed or sprung away from the surface upon which it is placed is not new. I do not claim these, broadly.

I am aware that prior to my invention a key-fastener consisting in a vibratory plate having a key-hole and a communicating slot at right angles to the enlarged opening in said key-hole was employed, and that the shoulder at the intersection of said slots was cut away.

What I claim and wish to secure is as follows:

1. In a key-fastener, the combination of an outer plate provided with an opening and communicating slot, constituting a key-hole, a laterally movable plate provided with an opening and two communicating slots at right angles to each other, the opening in said movable plate and one of the communicating slots therein corresponding to the key-hole in the outer plate aforesaid, and being adapted to receive a key when said opening, slot, and key-

hole register, the inner shoulder on said movable plate at the intersecting point between the two communicating slots being rounded, so as to turn the key when the plate is moved, substantially as specified.

2. In a key-fastener, in combination with a sliding plate adapted to secure the key within the lock, a plate, A, having the slot d formed therein, a pin, C, having a shank adapted to pass through said slot and lock said plate, and having attached a cam, e, substantially as described.

3. In a key-fastener, in combination with a movable plate adapted to secure the key within the lock, a plate having a slot formed therein, said slot having lateral enlargements, and a pin passing through said slot and attached to said plate, said pin having attached a cam having a projection formed thereon, and adapted to lock said plate, substantially as described.

JOSEPH S. RANDALL.
